UNITED STATES PATENT OFFICE.

JOHN PEPERNICK, OF BINGHAMTON, NEW YORK.

BED SPRING.

Application filed June 4, 1926. Serial No. 113,795.

This invention relates to improvements in bed springs and has for its object the provision of a bed spring construction wherein the springs proper will be positively anchored with respect to the frame portions thereof, and consequently, insuring collective and efficient functioning of the springs upon application of stress thereto and hence rendering the device comfortable and restful to a person reclining thereon.

It is also among the aims and objects of the invention to provide a bed spring consisting of a plurality of relatively interconnected spring units, such units constituting, each in itself, a portion of the spring frames or sides, and which, should it become necessary, can be removed from the assembly for repair or replacement.

Other objects of the invention will be in part obvious and in part pointed out hereinafter.

In order that the invention and its mode of operation may be readily understood by others skilled in the art, I have in the accompanying illustrative drawings and in the detailed following description based thereupon, set out one possible embodiment of the invention.

In the drawings:

Figure 1 is a fragmentary plan view of a bed spring constructed in accordance with the invention, and

Figure 2 is a disassembled detail in perspective of one of the spring units of the construction and one of the framing marginal portions or sides.

Having more particular reference to the drawings, in connection with which like characters of reference will designate corresponding parts throughout, it may be stated that a bed spring constructed in accordance with my invention comprises a plurality of relatively juxtaposed and interconnected coil spring units. Each of these units corresponds in the construction and therefore, in the description to hereinafter follow, reference will be had to but one of the units, such reference or descriptive matter sufficing for all of such units.

The improved spring unit may be stated to comprise a helical spring or coiled spring, indicated in its entirety by the numeral 1, the opposite end portions of said spring being bent upon themselves into horizontal planes and each providing framing units or portions designated by the numeral

2. These framing units or portions 2, as will be noted, are substantially square in configuration, the same starting from the opposite extremities of their respective 60 coiled or helical springs 1, being bent in a substantially right angular fashion as designated by the numeral 3 whereupon other right angularly disposed portions 4 are formed thereon while the free right angular extremity 5 is formed upon its respective free end with an eyelet or loop 6, the purpose of which will be presently described. Thus, it will be seen that each of the framing units or portions formed upon the opposite extremities of the various coiled or helical springs 1 will serve to constitute the usual spring frames or sides upon the opposite side of said spring when these springs are arranged in juxtaposed relationship in 75 the manner illustrated in the Figure 1.

With arrangement of the spring units in juxtaposed relation as disclosed in the Figure 1, it becomes desirable that they shall be provided with an effectual means for fixedly interconnecting the same and to this end, an eyelet 7 is formed in each of the portions 3 directly adjacent the junction of the framing units with their respective portions of the coiled springs 1 whereas other eyelets or loops 8 are formed in the intermediate portions of the sides 4. The loops 6 aforesaid, correspond in size and shape to the loops or eyelets 7 and 8. Those loops or eyelets upon the adjacent portions of the 90 juxtaposed spring units are adapted to be arranged in overlapping relationship whereupon fastening devices such as indicated by the numeral 9 are passed through the overlapping and aligned adjacent loops or eyelets and are secured therein against accidental or undue displacement. Thus, a means is effected for maintaining the various spring units in their assembled relation and against relative horizontal or displacing 95 movement. At the same time, it will be appreciated that because of the juxtapositioning of the framing units constituted by the portions 3, 4 and 5 upon the extremities of the various coiled springs 1, it will be understood that efficient sides or frames are 100 provided the said spring device.

With a view toward providing the outer marginal portions of the spring units with means for fixedly interconnecting the same 110 and furthermore, for providing the said spring frames so constituted by the framing

units with marginal or side portions, rods generally designated by the numeral 10 are employed, the same having right angular bends 11 formed therein to constitute the 5 corner portion of the completed bed spring assembly, while a plurality of inwardly disposed and equi-spaced loops 12 are formed therein throughout their length and are so disposed as to overlap and align with the 10 particular loops or eyelets upon the adjacent portions of the framing units of the springs units, as constituted by the portions numbered 3, 4 and 5, hereinbefore described. With overlapping and aligning arrangement 15 as between the loops 12 upon the side rods 10 of the said spring device, fastening devices 9' are passed therethrough, as is shown in the Figure 1 and thus, effectual sides are provided for the frames constituted by the 20 framing units on the opposite end portions of certain of the helical springs 1.

From the foregoing, it will be understood that I have provided a highly practicable and yet simple construction and assembly of 25 said spring device, the construction of the spring units and their relative assembly being such as to absolutely prevent any displacement of the various helical springs 1 with respect to the frames or opposite sides 30 of the construction as constituted by the framing units consisting of the portions 3, 4 and 5. This displacement of the coil spring 1, as will be readily understood, is positively prevented because of the fact that the various framing units of the different springs 35 are integral with the opposite extremity thereof and by consequence, since said framing units are fixedly interconnected when arranged in their juxtaposed relation as 40 shown in the Figure 1, it must necessarily

follow that displacement of the coil spring 1 will be prevented. Furthermore, it will be understood by workers skilled in the art that in addition to materially reducing construction costs of a bed spring construction by the 45 absence of separate spring frames or anchoring means, my improved bed spring construction permits of the removal of any one or more spring units for repair or replacement, such as conditions or preference may 50 dictate, the rearrangement and reinterconnection of the particularly removed spring unit being readily effectible and in no way affecting the proper operation of the device.

Manifestly, the construction shown is capable of considerable modification and such modification as is within the scope of my claim, I consider within the spirit of my invention.

I claim:

A bed spring comprising a plurality of juxtaposed helical springs, the opposite portions of each of said springs being bent in substantially right angular fashion to constitute approximately square framing units, 65 portions of the various sides of said framing units having loops formed therein, the loops upon the adjacent portions of such framing units being adapted to be arranged in overlapping and aligning relation, securing means passing through the overlapping and aligned loops, and side rods having equi-spaced loops formed therein adapted to overlie and align with certain of the loops upon said framing units and to be fixedly 70 connected thereto.

In witness whereof I have hereunto set my hand.

JOHN PEPERNICK.
